UNITED STATES PATENT OFFICE.

KNUD VALDEMAR ROTZOV, OF MÄLMO, SWEDEN.

DEVICE FOR AUTOMATICALLY CLOSING COCKS AND THE LIKE.

1,031,874.

Specification of Letters Patent.

Patented July 9, 1912.

Application filed June 30, 1910. Serial No. 569,687.

To all whom it may concern:

Be it known that I, KNUD VALDEMAR Rotzov, subject of the King of Denmark, residing at Malmö, Sweden, have invented new and useful Improvements in Devices for Automatically Closing Cocks and the Like, of which the following is a specification.

My invention relates to improvements in automatic closing devices for cocks more especially intended for use in connection with gas or petroleum stoves, but which may be employed in all relations where the performance of a similar function is required, for instance in connection with electric cut 15 outs on electric cooking apparatuses.

The purpose of the invention is to provide means for automatically closing the fuel supply, *i. e.* extinguishing of the flame.

The invention consists in the novel construction and combination of parts, as is hereinafter described and defined in the appended claims.

Reference is to be had to the accompanying drawings forming a part of this specification in which--

Figure 1 is a view in side elevation of a gas stove combined with the closing device, parts of the latter being shown in section for the sake of clearness. Figs. 2 and 3 show modifications of the invention.

The gas stove is in the drawing indicated by 1. At the upper part of the cooking vessel 2 or on its cover a short pipe 3 is applied, the outer free end of which points toward 35 a funnel shaped expansion on a pipe 5 extending from a box 4. The lower part of this pipe ends over a cup 7 which is carried up by a lever 6. A counterweight 8, a spring or the like acts upon the other end of the

40 lever. When the steam commences to escape from pipe 3 and strikes the funnel, it becomes condensed and flows by drops through the pipe 5 wherefrom it falls into the cup 7. Then the equilibrium of the level is altered so that a circuit with an electromagnet 45 becomes closed. A mercury cup 10, wherein the lever arm is pressed down by the weight of condensed waterdrops, is suitably used as a contact maker. This mercury switch is

50 connected with a terminal 12 by means of a conducting wire 11 and the lever 6 is connected with the terminal 14 by means of a wire 13. The armature 15 of the electromagnet consists of a lever provided at one 55 of its ends with a hook 16 or the like adapted

to engage an arm 18 which is fastened to the plug 17 of the gas cock and which is provided with a weight 19. By making the contact between the lever 6 and the mercury cup the armature 15 is attracted. Then the hook 16 releases the arm 18 which falls down together with the weight 19. By this movement the cock becomes partly or entirely closed according to as the arm 18 sooner or later hits a projection or the like 20. The bottom of the cup 7 is suitably slanting, so that one of its edges reaches up to the upper edge of the cup and the water drops may flow out when cup moves downward. After the cup thus having been emptied it raises 70 itself and cuts off the current. The armature 15 is journaled on the tap 24 and rests with its heavier arm against a pin 25 as long as the circuit is broken. When the lever 6 is provided with the adjustable counterweight 8, the interruption of the cooking can be retarded by adjusting the weight.

Instead of the steam being caught and condensed in a separate pipe or the like it may be condensed in a pipe or the like connected with the vessel 2 so that the condensed drops fall directly from the cooking vessel upon the releasing device, as shown in Fig. 2.

In order to be independent of having the pipe 3 pointing toward the funnel or releasing device the cooking vessel may be provided with a ringshaped opening through which the steam can escape in all directions, as shown in Fig. 3. In whatever direction 90 the vessel then may be turned the steam always strikes the funnel or if the steam is condensed already in the ring shaped opening, the drops always fall upon the releasing device.

Having thus described my invention I claim as new and desire to secure by Letters Patent:

1. In a device of the class described, in combination, a cooking apparatus, means for regulating the supply of heat-producing medium and means positioned externally of said cooking apparatus controlled by the condensation from steam from the liquid being boiled on the apparatus to actuate said first-mentioned means.

2. In a device of the class described, in combination, a cooking apparatus, means for regulating the supply of heat-producing medium and means controlled by the con-

- densation from steam from the liquid being boiled on the apparatus to actuate said first-mentioned means.
3. In a device of the class described, in combination, a cooking apparatus, means for regulating the supply of fuel thereto, and means controlled by the condensation from steam from the liquid being boiled on the apparatus to actuate said first-mentioned means.
4. In a device of the class described, in combination, a cooking stove, a valve for regulating the supply of gas thereto, and means controlled by the condensation from steam from the liquid being boiled on said stove to close said valve.
5. In a device of the class described, in combination, a cooking apparatus, means for regulating the supply of fuel thereto, and means controlled by the condensation from steam from the liquid being boiled on the apparatus to actuate said first-mentioned means, said second-mentioned means comprising a pivoted lever provided with a receptacle to receive the condensed steam.
6. In a device of the class described, in combination, a cooking apparatus, means for regulating the supply of fuel thereto and means controlled by the condensation from steam from the liquid being boiled on the apparatus to actuate said first-mentioned means, said second-mentioned means comprising a pivotally mounted lever provided with a receptacle adapted to receive the condensation from steam adjacent one end thereof and means for normally maintaining said lever in a substantially horizontal position, said receptacle being provided with an inclined bottom whereby as the lever is moved downward under the action of the condensation from steam which is collected in the receptacle, the condensation from steam is allowed to escape from the receptacle, permitting said third-mentioned means to move the lever to its normal position.
7. In a device of the class described, in combination, a cooking apparatus, means for regulating the supply of fuel, said means tending normally to occupy a closed position whereby the supply of fuel will be stopped, a member releasably holding said first-mentioned means in open position, and means controlled by the condensation from steam from the liquid being boiled on the apparatus to actuate said member to release said first-mentioned means whereby the latter may assume its closed position.
8. In a device of the class described, in combination, a cooking apparatus, a valve for regulating the supply of fuel thereto, said valve tending normally to occupy its closed position whereby the supply of fuel will be stopped, a member releasably holding said valve in its open position, an electromagnet adapted upon energization to actuate said member to release said valve, a normally-open circuit containing said magnet and a circuit-closer for closing said circuit, said circuit-closer being actuated by the condensation from steam from the liquid being boiled upon said apparatus.
- In testimony whereof I have signed my name to this specification in the presence of two subscribing witnesses.
